LEVELING MACHINE

Andrew Eppler, Lynn, Mass., assignor to United Shoe Machinery Corporation, Paterson, N. J., a corporation of New Jersey

Application October 8, 1932. Serial No. 636,873

46 Claims. (Cl. 12—34)

This invention relates to machines for use in the manufacture of boots and shoes (hereinafter referred to generically as shoes) for performing what is known as the leveling operation. 5 The invention is herein illustrated as embodied in a machine of that type in which the shoe is operated upon progressively by relative movements of a shoe support and a leveling tool, such as a roll, in directions lengthwise of the shoe, 10 and in which the relative movements are effected by power-operated means continuously under control of the operator so that different portions of the sole of the shoe may be treated selectively in the manner determined by the 15 operator in accordance with the requirements of the particular shoe. It is to be understood, however, that in various novel aspects the invention is not limited to machines of that particular character.

20 An object of the invention, among others, is to provide improvements in machines of the above-mentioned type, to the end that shoes may be more effectively and satisfactorily treated than heretofore by the use of such machines. It 25 is also an object to provide a machine convenient for use and one that may be operated and controlled with but little effort on the part of the operator. To these and other ends, the machine herein shown, in one important aspect, comprises 30 novel means whereby relative movements of the shoe support and the leveling tool are effected and controlled in such manner as to permit the extreme toe end of the sole to be satisfactorily treated without any danger of excessive 35 bending of the margin of the sole by the action of the tool thereon. In the construction shown the shoe support or jack is moved relatively to the leveling roll in directions lengthwise of the shoe by power-operated means which is 40 continuously under control of the operator as and for the purpose hereinabove described; and mechanism is provided for imparting automatically to the roll, in predetermined relation to the movement of the shoe support, movement height- 45 wise of the shoe into initial engagement therewith on the bottom face of the toe end of the sole and reverse movement finally out of engagement with the shoe from a position in the same relation to the toe end of the sole. There 50 is accordingly no danger of excessive bending of the margin of the toe end of the sole by running of the roll on or off the shoe. As herein illustrated, the roll receives its movement into engagement with the shoe prior to the first rear- 55 ward movement of the shoe support (i. e., move-

ment of the support in a direction away from the operator), and is carried out of engagement with the shoe only after the final forward movement of the shoe support, the movements of the roll and the shoe support being effected under 60 control of power-driven cams shaped and arranged for the accomplishment of these results. By reason of this construction the proper leveling of the toe end of the sole is facilitated, since the operator may readily bring the machine to a 65 stop with the shoe support at the limit of its forward movement and the roll in engagement with the toe end of the sole, after which he may tip the roll laterally of the shoe by means provided for that purpose to shape the toe end of 70 the sole properly throughout its width. To facilitate the mounting of the shoe on the shoe support and its removal therefrom, the construction shown is also such that the roll is moved length- 75 wise of the shoe in forward and rearward directions simultaneously with its movements heightwise thereof as above-described, so that it is well retracted from over the toe end of the shoe prior to and after the leveling operation; and in this aspect a novel feature of the invention is further 80 to be recognized in means for imparting to the leveling tool positioning and retractive movements lengthwise of the shoe.

As a further feature, the invention provides novel means whereby the leveling tool may be 85 controlled by the operator in such manner as to apply the leveling pressure selectively to one or more portions of the shoe bottom without pressure on other portions or to vary the amount of pressure applied. As herein illustrated the leveling roll is pressed down upon the shoe bottom by power-operated means including a rod connected to a vertically swinging carrier that supports the roll, and for the purpose in view there is provided treadle-operated mechanism arranged to act through this rod to support the roll or lift it from the shoe at any time when the operator so desires.

Facility in the control of the machine is further afforded, in the construction shown, by the 100 provision of hand-operated members at opposite sides of the machine, one for controlling the power operation of the machine and the other for tipping the roll laterally of the shoe, combined with means whereby the roll is pressed upon 105 the shoe bottom as a part of the power operation without special attention on the part of the operator. Accordingly all that the operator has to do under most operating conditions is to manipulate these two controlling members. On 110

the other hand, at any time when it is desirable for the operator further to control the leveling roll by use of the above-mentioned treadle, he is free to do so since there is no other member 5 which he is required to control with his foot.

The above and other features of the invention, including various novel details of construction and combinations of parts, will now be more particularly described by reference to the accompanying drawings and pointed out in the claims. 10

In the drawings,

Fig. 7 is a section on the line VII—VII of Fig. 6;

Fig. 8 is a view partly in end elevation and partly in section on the line VIII—VIII of Fig. 6;

30 Fig. 9 is a section on the line IX—IX of Fig. 3, and

Fig. 10 is a section on the line X—X of Fig. 3.

The main frame 20 of the illustrated machine has pivotally connected thereto a shoe support 35 or jack 22 to which swinging movements are imparted by power-operated mechanism, hereinafter described, to carry the shoe back and forth beneath a leveling roll 24 which is yieldingly forced down on the shoe bottom to apply leveling

40 pressure progressively to the sole and to which lateral tipping movements may be imparted by means under control of the operator to cause the leveling pressure to be applied to the margins of the sole. The jack 22 is in many respects similar to the disclosure of Letters Patent No. 1,239,664, granted on September 11, 1917 upon an application of W. C. Baxter, and comprises a

45 toe post 26 fulcrumed on a short transversely extending shaft 28 mounted in suitable bearings 50 in the frame 20 and a heel post 30 also fulcrumed on the shaft 28 and connected to the toe post by a threaded adjusting rod 32. The rod 32 is provided with oppositely threaded portions which

55 engage members 35, 37 pivotally connected respectively to the toe and heel posts 26, 30. Fast to the outer end of the rod 32 is a hand wheel 34 for turning the rod to move the heel post 30 toward or from the toe post and thus to vary the size adjustment of the jack to accommodate

60 shoes of different lengths. It will be evident that by this adjustment the ends of the toes of shoes of different lengths are positioned in substantially the same location. The toe and heel posts are provided with means for supporting a

65 shoe and last for the leveling operation comprising a self-adjusting toe support 36 carried by the toe post 26 and a spindle 38 carried by the heel post 30, the construction being such that a long-legged boot also may be supported on the jack.

70 The spindle 38 extends through an enlarged opening formed in a plate 40 also carried by the heel post 30, which plate is free to tip about an axis extending laterally of the shoe to adjust itself to the top face of the cone of the last. This plate and the toe support 36 are constructed

substantially as disclosed in a copending application of mine, Ser. No. 628,354, filed August 11, 1932, and accordingly are not described herein in detail. The spindle 38 is carried by a block 42 which is pivoted at 44 to the top of the heel post 30 to swing in directions lengthwise of the shoe. The block 42 is connected by a link 46 to mechanism which will presently be described whereby the block and spindle may be swung to press the toe end of the shoe firmly down upon the toe support 36.

The illustrated machine may also be provided with a saddle 48, shown in Fig. 5 but omitted from the other views, for use in jacking a shoe alternatively with the spindle-tipping mechanism just referred to. The saddle 48, similarly to the disclosure of Letters Patent No. 1,263,361, granted on April 23, 1918 upon an application of W. C. Baxter, is connected to the two arms of a bifurcated lever 50 by strong springs 52, and when the saddle is used the lever 50, the arms of which are pivoted at 54 to blocks slidingly mounted in slots 56 on the toe post 26, pulls it down tightly over the shoe and is then locked to a segment 58 on the heel post. The slots 56 are concentric with the shaft 28 to permit relative movements of the toe and heel posts without disturbing the relation between the lever 50 and the heel post, as explained in the last-mentioned Letters Patent.

The relation of the lever 50 to the spindle-tipping mechanism will now be described. Pivotally connected at 60 to the heel post 30, one on each side thereof, are links 62 the rear ends of which are connected to the arms of the lever 50 by short upwardly extending links 64. The 105 links 62 have pivotally connected thereto at 66 downwardly extending links 68 which carry a horizontal pin 70 extending through a slot 72 formed in a member 74 (Figs. 1 and 5) pivoted to the lower end of the link 46. Pivotally connected to the member 74 is a member 76 which 110 may be swung up into position to serve as an abutment for the horizontal pin 70, as shown in Figs. 1, 2 and 4, or down as shown in Fig. 5. When the member 76 is in the latter position the pin 115 70 has free movement in the slot 72 as the lever 50 is swung downwardly so that no motion is imparted to the link 46 in operating the saddle 48. When the member 76 is in the position shown 120 in Figs. 1, 2 and 4 downward movement of the 125 lever 50 forces the link 46 downward to operate the spindle 38 by engagement of the pin 70 with the member 76. The member 76 is held in the position shown in Figs. 1, 2 and 4 by a spring-pressed pin 78 which enters a hole 80 therein (Fig. 5). 130 The mechanism for thus rendering the lever 50 effective to operate either the saddle 48 or the link 46 is generally similar to the disclosure of Letters Patent No. 1,719,158, granted on July 2, 1929 upon an application of E. E. Winkley and 135 H. A. Davenport.

In the illustrated machine the jack 22 as a whole is swung about the shaft 28 by a cam 90 and connections therefrom to the jack which may be adjusted to vary the extent of the swinging movements of the jack in accordance with the length of the shoe being operated upon. The cam 90 is formed in one side of a cam wheel 92 carried by a cam shaft 94 which is mounted transversely in the frame 20 and is connected to 140 power-operated means, hereinafter described, which is continuously under manual control and is arranged to rotate the cam wheel 92 in opposite directions at the will of the operator to impart to the jack its swinging movements. As shown 145

particularly in Fig. 5, the toe post 26 is provided with a rearwardly extending arm 98 connected by means of a link 100 to a rocking lever 102 which is pivoted at 104 to the frame 20 and carries at its rear end a roll 106 engaged by the cam 90. The arm 98 and the lever 102 are provided respectively with segmental slots 108, 110, in which there are slidably mounted blocks 112, 114, pivotally connected to the ends of the link 100. The link 100 is pivotally connected intermediate its ends at 116 to a link 118 pivoted at 120 to the frame 20. The jack 22 is thus oscillated by the rocking of the lever 102 about its fulcrum and its amplitude of oscillation can be adjusted by swinging the link 100 about its pivot 116 to vary the effective lengths of the arm 98 and the lever 102.

For adjusting the position of the link 100 there is provided a lever 122 fulcrumed at 124 to the arm 98. The lever 122 is connected by means of a link 126 to a downwardly extending arm 128 with which the heel post 30 is provided and has pivotally connected to its upper end a member 130 in which there is rotatably mounted a spindle 132. The spindle 132 is provided with a rearwardly extending threaded portion which extends through a member 136 pivoted on the upper end of the link 100. The spindle 132 is held against lengthwise movement relatively to the member 130 by oppositely disposed collars 133. The construction is therefore such that as the heel post 30 is swung about its fulcrum 28 by movement of the threaded adjusting member 32 in accordance with the length of the shoe to be operated upon the link 100 is moved along the segmental slots 108, 110 to vary correspondingly the extent of the swinging movements of the jack. When the parts are in their inoperative or idle positions, the segmental slots 108, 110 are concentric with the fulcrum 116 of the link 100 so that this adjustment may be made without moving the toe post 26. The parts are therefore so designed that the extent of the swinging movement imparted to the jack 22 by the cam 90 is proportional to the size adjustment of the jack. In order further to vary the extent of the swinging movements of the jack to accommodate shoes of different styles, there is provided means for initially adjusting the position of the link 100 relatively to the arm 98 and the lever 102 without adjustment of the jack. As shown in Fig. 5, there is rotatably mounted in the member 130 a rod 140 which is held against lengthwise movement relatively to the member 130 by a collar 142 and a skew gear 144 which is fast on the rod 140 and the teeth of which mesh with the teeth of a skew gear 146 fast on the spindle 132. The rod 140 extends forwardly and has secured to its outer end a hand wheel 148 conveniently accessible to the operator and by means of which the rod and the spindle 132 may be rotated to move the link 100 along the segmental slots 108, 110 without disturbing the size adjustment of the jack.

The machine herein shown is so constructed that the leveling roll 24 is maintained initially in a position higher than that which it occupies in operating upon the shoe and in which also it is retracted rearwardly lengthwise of the shoe. In predetermined relation to the first rearwardly swinging movement of the jack, prior to the beginning of such movement, the roll receives a forward positioning movement and is also swung downwardly to carry it into initial engagement with the shoe on the bottom face of the toe end of the sole, thus insuring against any damage to the sole or undue bending of its margin at the toe end by contact of the roll with its edge. The roll is mounted for turning movement on the rod 159 supported by a holder 160 and is movable also lengthwise of the rod, springs 161 being provided at the opposite ends of the roll which normally centralize it lengthwise of the rod but permit it to move in one direction or the other along the rod for better accommodation to the shapes of different portions of the shoe bottom. The holder 160 is a yoke-shaped device, portions of which are slidably movable lengthwise of the shoe in guideways formed in the arms of a forked roll carrier 162 which is clamped at 164 to the forward end of a hollow shaft 166, this shaft being mounted for turning movement in an arm 168 provided with a forked rear end fulcrumed at 170 on the frame of the machine for swinging movements heightwise of the shoe. The holder 160 is provided with a depending lug 172 in which there is threaded the forward end of a rod 174 that extends rearwardly through the hollow shaft 166 and is connected at its rear end to a yoke 176 in which it is mounted for turning movement. At its forward end the rod 174 is shaped at 178 to receive a wrench by which it may be turned to adjust the holder 160 lengthwise of the shoe, the holder being held in adjusted position by a lock nut 180. The yoke 176 is connected to the upper end of a lever 182 by a link 184, the lever being fulcrumed at 186 on the frame 20, and pivotally connected to the lower end of the lever is one link 188 of a toggle, the other link 190 of which is pivoted to the frame. A tension spring 192 is connected at one end to the frame 20 and at its other end to a bar 194 connected to the knee joint of the toggle, the spring therefore acting, when permitted, to straighten the toggle and thereby to impart forward movement to the holder 160 and the roll 24.

The toggle is controlled by a peripheral cam 196 on the cam wheel 92 through a lever 198 which is connected to the bar 194 by a rod 200. The lever 198 is fulcrumed at 202 on the frame 20 and carries at its forward end a roll 204 (Fig. 2) engaged by the cam 196. The cam 196 is so shaped and arranged that at the beginning of the first turning movement of the cam wheel 92 from its initial position, prior to the swinging of the jack by the cam 90, it permits the spring 192 to straighten the toggle 188, 190, and thus to move the roll 24 forwardly to a position over the toe end of the sole before the roll engages the sole. In the final portion of the reverse turning movement of the cam wheel at the end of the operation of the machine upon the shoe, after the jack has arrived at the limit of its forward movement, the cam 196 acts through the lever 198 and the rod 200 to break the toggle and thus to move the holder 160 and the roll to a retracted position so as not to interfere with the removal of the shoe and the mounting of another shoe on the jack.

For controlling downward swinging movement of the arm 168 and for raising the arm to carry the roll 24 upwardly away from the shoe there is provided a rod 206 adjustable as to length and pivotally connected at 208 to the above-mentioned lever 198, the rod being provided at its upper end with a head 210 arranged to engage the lower side of the arm. It will thus be seen that as the roll 24 is moved forwardly at the time and in the manner above described the downward

movement of the rod 206 under control of the lever 198 permits the roll at the same time to be swung downwardly by the arm 168, and when the jack is at the limit of its final forward movement the roll is swung upwardly away from the shoe by the rod 206 simultaneously with its retractive movement lengthwise of the shoe effected by the swinging of the lever 198.

The downward swinging movement of the roll 24 which results from the above described downward movement of the rod 206 is effected yielding through a heavy spring 214 which is connected at one end to a lever 216 pivoted at 218 on the frame and at the other end to a rod 220 extending upwardly through the head 222 of a member 224 pivotally mounted on the arm 168, the rod being secured to the head 222 by clamping nuts 226 and 228. Formed on the cam wheel 92 is a peripheral cam 230 in engagement with a roll 232 (Fig. 4) mounted on a downwardly extending arm 234 of the lever 216. The cam 230 thus acts through the spring 214 to press the roll upon the shoe bottom with the required force. The cam is so shaped that when the jack 25 is in position for the roll to act on the downwardly curved shank portion of the shoe bottom the lever 216 is further depressed, thus not only compensating for the downward curve of the shank, but increasing the pressure of the roll upon this portion of the shoe bottom, which is desirable in view of the more pronounced transverse curvature of the shank portion of the sole as compared with the forepart. To limit the downward movement of the roll in case the machine is operated without any shoe on the jack, there is provided a screw 236 on the frame arranged to serve as an abutment in engagement with arm 168. The screw 236 is locked in adjusted position by a nut 238.

From the foregoing description it will be evident that the machine is so constructed as to prevent excessive bending of the margin of the toe end of the sole by the roll 24, such as might otherwise result from the action of the spring 214 on the arm 168 as the roll passes on or off the shoe, since the roll is always advanced to a position over the bottom face of the toe end of the sole before it engages the shoe and the jack in its forward movement never passes beyond a position in which the roll is in that relation to the sole, the roll being lifted from the shoe after the jack has arrived in that position.

The roll 24 may be tipped laterally of the shoe at various inclinations for operating along the side edges of the shoe bottom by turning movement of the previously-mentioned hollow shaft 166. For this purpose there is provided a lever 240 loosely mounted on the right-hand end of the shaft 28 and connected at 244 to a rod 246 which extends rearwardly through a member 248 (Fig. 4) and is fastened to this member by nuts 250, 252. The member 248 is pivoted on an arm 254 which is fast on one end of a shaft 260 (Fig. 3) rotatably mounted in the frame 20, the shaft having fast thereon a segmental bevel gear 264. The gear 264 engages a similar gear 266 fastened to the shaft 166 by a clamping screw 268. The lever 240 is provided with a handle portion 270 extending forwardly into a convenient position for use by the operator and by means of which the lever may be swung to tip the roll 24 as desired.

The construction of the machine is further such as to enable the operator to determine selectively the portions of the shoe bottom upon which the

leveling roll operates by control of the swinging movements of the arm 168. More particularly, as illustrated, the operator is enabled to swing the roll upwardly away from the shoe bottom at any time, or to hold it upraised so as not to contact with the shoe until some particular portion of the sole is positioned under the roll. For this purpose there is associated with the rod 220 a gripping device comprising a plurality of plates 272 (Fig. 2) controlled by a lever 274 and provided with apertures through which the rod 220 extends. The lever 274 is fulcrumed at 276 to the frame 20 and is connected by a rod 278 to a treadle 280 pivoted at 202 on the frame. A spring 282 holds the treadle normally in raised position against an adjustable stop 283. The plates 272 are clamped at one end against a depending lug 284 on the lever 274 by a screw 286 on the lever, while at their opposite ends they rest against an upstanding lug 288 on the frame 20 and are pressed downwardly against this lug by a spring plunger 290 on the lever 274. Normally, as shown in Fig. 2, the plates are thus positioned in such relation to the rod 220 as to permit the latter to move freely upwardly or downward through the apertures in the plates. If the treadle 280, however, is depressed by the operator, the upward swinging movement of the lever 274 causes the plates to tip and thereby grip the rod 220 and thus not only to prevent downward movement of the rod 105 but by further movement of the treadle to lift the rod. The operator may thus hold the roll upraised until the jack is in position for the roll to operate on the shank portion of the sole, in case it is desired to level the shank portion 110 without leveling the forepart. In operating, moreover, on shoes of the cottage shank type the operator may, after leveling one side of the shank with the roll in an inclined position, lift the roll 115 by the treadle and place it in an oppositely inclined position on the other side of the shank without engaging the central ridge of the sole. Use of the treadle, moreover, enables the operator to lessen at any time the force with which the roll is pressed down upon the shoe bottom 120 through the spring 214.

The cam wheel 92, through the operation of which the leveling roll is controlled automatically in the manner previously described and through which swinging movements also are imparted to the jack, is operated by power-driven means which is continuously under control of the operator so that he may interrupt the operation of the machine at any time and may also cause the jack to swing in one direction or the other as desired. For this purpose the shaft 94 on which the cam wheel is mounted has fast thereon a worm gear 292 (Fig. 6) engaged by a worm 294 on a shaft 296. The shaft 296 is driven in opposite directions at the will of the operator through oppositely disposed clutches 298, 300, the driving members of these clutches being constantly rotated in opposite directions and the driven members so mounted that either clutch can be made to drive the shaft 296 at will. In 130 the illustrated machine power is derived from a motor 302 (Figs. 1 and 3), which by means of a belt 304 drives a pulley 306 fast on the outer end of a short shaft 308 journaled in the frame 20 in parallel relation to the clutch shaft 296. Loosely 135 mounted on the clutch shaft 296 in spaced relation are a pair of gears 310, 312, the gear 312 being constantly rotated by a gear 314 (Fig. 9) fast on the shaft 308. The gear 310 is constantly rotated in the opposite direction through an idler 140

gear 316 (Fig. 10) which meshes with it and with a gear 318 fast on the shaft 308. The gears 310, 312 are provided, as shown, with laterally extending flanges 329, 322 which have internal 5 clutch surfaces and act respectively as the driving members of the opposed clutches 298, 300. Co-operating therewith are driven members 328, 330 carried by a sleeve 332 which is mounted for sliding movement lengthwise of the shaft 296 and is 10 connected to the shaft by splines 334. The sleeve 332 is moved lengthwise of the shaft 296 to move one or the other of the clutch members 328, 330 into engagement with its cooperating clutch member by a lever 336 which is pivoted at 340 15 to the frame 20 and has pivotally connected to its upper end a rod 342 which is connected at its opposite end by means of a yoke 344 to the upper end of an arm 346 fast on the right-hand end of a rock shaft 348 journaled in the front of the frame 20. The lever 336 has a downwardly extending arm 350 which is bifurcated to straddle the sleeve 332, and pivotally connected to the lower end of this arm are blocks 352 which fit 20 between thrust washers 354, 356 mounted on the sleeve 332 between the blocks and the clutch members 328, 330. Loosely mounted on the left-hand end of the rock shaft 348 (Figs. 1 and 2) is a lever 358 carrying at its upper end a handle 360. The lever 358 is secured, as shown, to a 25 second lever 362 fast on the rock shaft 348 by means of bolts 364, 366, which extend respectively through arcuate slots 368, 370 formed in the lever 362, the construction thus being such that the lever 358 may be adjusted relatively to the lever 362 to move the handle 360 into a convenient position to be grasped by the hand of the operator. It will be understood that by the use 30 of the handle 360 the lever 358 may be swung to move the sleeve 332 either forwardly or rearwardly to connect either of the friction clutches 298, 300, to the shaft 296, thus causing the jack 22 to be swung in either direction desired. The lever 358 is held normally in an idle position with the machine at rest by equalizing springs 374, 376 which surround the rod 342 and bear at their inner ends against a lug 378 on the frame 20 and at their outer ends against collars 380, 382 fastened to the rod 342.

The illustrated machine is further provided 35 with means for automatically throwing the above-described friction driving mechanism out of operation and moving the handle 360 to its idle position if the cam wheel 92 is turned beyond a predetermined point in either direction, thus insuring against damage to the machine. As 40 shown, this means comprises a pin 384 which is carried by the worm wheel 292 and is arranged to engage the rearwardly extending arm 386 of a bell-crank lever fulcrumed at 390 on the frame 45 of the machine. This lever is provided with a depending arm 392 which is forked to straddle a bushing 394 (Fig. 7), the bushing being threaded on the rod 342 and held in adjusted position by a lock nut 396. Surrounding the bushing 394 on opposite sides of the depending forked arm 392 are springs 398, 400. These springs bear at their outer ends against adjusting nuts 402, 404, threaded on the opposite end portions of the bushing 394, and between the inner ends of the springs and 50 the opposite side faces of the depending arm 392 are provided washers 406, 408. The construction is accordingly such that if the cam wheel 92 is turned beyond a definite point in either direction the pin 384 engages the arm 386 and through the yielding connections above described moves

the rod 342 in the direction to disconnect the friction driving mechanism from the shaft 296. It will be seen that in this movement the rod 342 also acts through the arm 346 to rock the shaft 348 in a direction to move the clutch-controlling lever 358 and the handle 360 to idle position. 80

Simultaneously with the throwing out of the friction driving mechanism, either by the above-described safety device or by normal use of the hand lever 358, a brake band 410 is applied to a brake drum 412 on the shaft 296 so as to hold the shaft from further rotation. The brake band 410 is provided with a downwardly extending arm 414 which is clamped to a depending lug 416 on the frame 20 by a bolt 418 and with a laterally extending arm 420 arranged to be engaged by an adjustable screw 422 carried by a lever 424 fulcrumed at 426 on the frame of the machine. The lever 424 has pivotally connected to it at 428 one member 430 of a toggle the other member 432 of which is pivoted at 434 to the frame 20. The member 432 of the toggle is provided with a pair of upwardly extending arms 436, 438 which are slotted to receive a pin 440 carried by a member 442 clamped to the rod 342. With this construction, when the rod 342 is moved in either direction to disconnect the friction driving mechanism from the shaft 296 the toggle member 432 is swung about its pivot 434 to straighten the toggle. 100 Straightening of the toggle causes the lever 424 to be swung downwardly and through the screw 422 to apply the brake band 410 to the brake drum 412, thus holding the shaft 296 from rotation. When the rod 242 is moved in a direction to 105 connect one or the other of the clutches 298, 300, to the shaft 296 the toggle member 432 is swung about its pivot to break the toggle and release the band 410 from the drum 412.

In the operation of the machine, briefly summarized, the operator mounts a shoe on the spindle 38, turns the hand wheel 34, if necessary, to adjust the jack to the length of the shoe, and then by movement of the lever 50 tips the spindle 38 to clamp the shoe firmly on the toe support 110 36. It will be understood that if the saddle 48 is to be used, the spindle-tipping mechanism will be disconnected from the lever 50 by turning the abutment member 76 downwardly and the shoe will be pressed firmly against the toe support 36 115 120 by the saddle 48 when the lever is operated. The operator then grasps the handle 360 and by pushing upon it connects the clutch 298 to the shaft 296 to cause the cam wheel 92 to be rotated in a clockwise direction as viewed in 130 Fig. 2. The first result of this movement of the cam wheel is that the lever 198 is permitted to turn in a counterclockwise direction by its controlling cam 196 under the influence of the spring 192, the latter accordingly straightening 135 the toggle 188, 190 to impart forward movement to the roll 24. Simultaneously the rod 206 is lowered by the lever 198, thus permitting downward swinging movement of the arm 168 and the roll 24 under the influence of the spring 214. 140 The roll is accordingly moved in an inclined path indicated diagrammatically at *a* in Fig. 2 so as to engage the shoe initially upon the bottom face of the toe end of the sole in such a location as to avoid any excessive bending of the margin of the 145 sole, yet near enough to the end of the toe to permit proper leveling of the toe portion of the sole. It will be understood that the location in which the roll thus first engages the shoe may be varied by adjustment of the roll holder 160 150

through turning movement of the rod 174. By reason of the relation of the cam 196 to the jack-operating cam 90 the above-described movement of the roll takes place prior to any movement of the jack. If the operator continues to push upon the handle 360 the cam 90 next becomes effective to impart to the jack its first rearward movement to cause the leveling roll to operate progressively along the shoe bottom, during 10 which movement and thereafter during such other movements as the jack receives the operator may, by use of the handle 270, tip the roll 24 in one direction or the other at any desired inclination for applying the proper leveling pressure to the margin of the sole. At any time, moreover, by control of the handle 360 the operator may stop the movement of the jack and may throw the clutch 300 into operation to reverse the direction of the movement. A plurality 20 of short movements of the jack may thus be effected while the roll is operating upon some particular portion of the shoe bottom, such as the shank. A forward movement of the jack also may be effected to the limit determined by 25 the shape of the cam 90, whereupon the operator may bring the machine to a stop with the roll still in contact with the toe end of the sole and may then tip the roll to assist in properly leveling this portion of the sole. If it should 30 be desired at any time to prevent the roll from operating upon some particular portion of the shoe bottom, for example to prevent it from engaging the sole at the ball line in operating upon shoes of certain styles or to prevent it from 35 engaging the sole along the central line of the shank in operating on cottage shank shoes, the operator may lift the roll from the shoe by depression of the treadle 280. When the leveling operation has been satisfactorily completed the 40 cam wheel 92 is made to turn far enough in one direction to lift and retract the leveling roll lengthwise of the shoe, such movement of the roll occurring after the jack has arrived at the limit of its forward movement. The operator 45 may then remove the shoe and mount another one on the jack, the roll 24 occupying such a retracted position as not to interfere in any way with these operations.

Having described the invention, what I claim 50 as new and desire to secure by Letters Patent of the United States is:

1. In a leveling machine, a shoe support, a leveling tool, means for moving said shoe support in 55 directions lengthwise of a shoe thereon to cause the leveling tool to operate progressively along the shoe bottom, and mechanism for imparting to said leveling tool a movement lengthwise of the shoe from a retracted position to a position over the toe end of the shoe bottom prior to the 60 operation of said tool upon the shoe.

2. In a leveling machine, a shoe support, a leveling tool, power-operated means for moving said shoe support in directions lengthwise of a shoe thereon to cause the leveling tool to operate progressively along the shoe bottom, and power-operated means for imparting to said leveling tool a positioning movement lengthwise of the shoe in automatically determined relation to the 65 movement of the shoe support prior to the operation of said tool upon the shoe.

3. In a leveling machine, a shoe support constructed to receive a shoe with its toe end pointing rearwardly, a leveling tool, power-operated means for moving said shoe support in directions 70 lengthwise of a shoe thereon to cause the leveling

tool to operate progressively along the shoe bottom, and automatic means for maintaining said tool initially in a rearwardly retracted position and for imparting to it a forward positioning movement substantially at the beginning of the 80 operation of the machine.

4. In a leveling machine, a shoe support, a leveling roll, power-operated means for moving said shoe support in directions lengthwise of a shoe thereon to cause the roll to operate progressively along the shoe bottom, and mechanism constructed and arranged to maintain said roll initially in a position retracted from over the bottom of the shoe and to impart to it a movement lengthwise of the shoe to a position over the toe end of the shoe bottom in automatically determined relation to the movement of the shoe support prior to the operation of said roll upon the shoe.

5. In a leveling machine, a shoe support constructed to receive a shoe with its toe end pointing rearwardly, a leveling roll, power-operated means for moving said shoe support in directions lengthwise of a shoe thereon to cause the roll to operate progressively along the shoe bottom, 95 and cam-controlled means for imparting to said roll a forward positioning movement in automatically determined relation to the movement of the shoe support prior to the operation of the roll upon the shoe.

6. In a leveling machine, a shoe support, a leveling roll, power-operated means comprising a cam for moving said shoe support in directions lengthwise of a shoe thereon to cause the roll to operate progressively along the shoe bottom, 100 mechanism for imparting to said leveling roll a movement lengthwise of the shoe to a position over the toe end of the shoe bottom substantially at the beginning of the operation of the machine, and a cam movable in fixed relation to said first- 110 mentioned cam for controlling said mechanism.

7. In a leveling machine, a shoe support constructed to receive a shoe with its toe end pointing rearwardly, a leveling roll, power-operated means for moving said shoe support in directions length- 120 wise of a shoe thereon to cause the roll to operate progressively along the shoe bottom, mechanism comprising a spring-operated toggle for imparting to the roll a forward movement substantially at the beginning of the operation of the machine, 125 and a cam arranged to control said toggle.

8. In a leveling machine, a shoe support, a leveling roll, power-operated means for moving said shoe support in directions lengthwise of a shoe thereon to cause the roll to operate progressively along the shoe bottom, a roll carrier movable heightwise of the shoe to press the roll upon the shoe bottom, and automatic means for imparting to the roll a positioning movement lengthwise of the shoe relatively to said carrier substantially at the beginning of the operation of the machine prior to the operation of the roll upon the shoe.

9. In a leveling machine, a shoe support, a leveling tool, power-operated means for moving said shoe support in directions lengthwise of a shoe thereon to cause the leveling tool to operate progressively along the shoe bottom, and automatic means for imparting to said tool a movement lengthwise of the shoe from a retracted 140 position to a position over the toe end of the shoe bottom prior to the movement of the shoe support.

10. In a leveling machine, a shoe support constructed to receive a shoe bottom upward with its 145

- toe end pointing rearwardly, a leveling roll, power-operated means for imparting to said shoe support first a rearward movement and thereafter forward and rearward movements to cause the roll to operate progressively along the shoe bottom, and automatic means for imparting to said roll forward movement from a retracted position to a position over the toe end of the shoe bottom prior to the first rearward movement of the shoe support. 5
11. In a leveling machine, a shoe support, a leveling tool, power-operated means continuously under control of the operator for moving said shoe support in opposite directions at the will of the operator to cause said tool to operate progressively along the shoe bottom, and power-operated means for imparting to said leveling tool a positioning movement lengthwise of the shoe in automatically determined relation to the first movement of the shoe support prior to the operation of said tool upon the shoe. 10
12. In a leveling machine, a shoe support constructed to receive a shoe with its toe end pointing rearwardly, a leveling roll, power-operated means continuously under control of the operator for moving said shoe support first rearwardly and thereafter forwardly and rearwardly at the will of the operator to cause the roll to operate progressively along the shoe bottom, and mechanism for imparting to said roll a forward positioning movement in automatically determined relation to the first rearward movement of the shoe support prior to the operation of the roll upon the shoe. 15
13. In a leveling machine, a shoe support, a leveling roll, power-operated means continuously under control of the operator for moving said shoe support in opposite directions at the will of the operator to cause the roll to operate progressively along the shoe bottom, and cam-controlled means for imparting to said roll movement from a retracted position to a position over the toe end of the shoe bottom prior to the first movement of the shoe support. 20
14. In a leveling machine, a shoe support, a leveling tool, means for moving said shoe support in directions lengthwise of a shoe thereon to cause the leveling tool to operate progressively along the shoe bottom, and mechanism for imparting to said leveling tool movement lengthwise of the shoe from a retracted position to a position over the toe end of the shoe bottom and for also moving it heightwise of the shoe toward the shoe bottom prior to the operation of the tool upon the shoe. 25
15. In a leveling machine, a shoe support, a leveling roll, power-operated means for moving said shoe support in directions lengthwise of a shoe thereon to cause the roll to operate progressively along the shoe bottom, and mechanism for imparting to said roll positioning movement lengthwise of the shoe and also movement heightwise of the shoe toward the shoe bottom in automatically determined relation to the movement of the shoe support. 30
16. In a leveling machine, a shoe support constructed to receive a shoe bottom upward with its toe end pointing rearwardly, a leveling roll, power-operated means for moving said shoe support in directions lengthwise of a shoe thereon to cause the roll to operate progressively along the shoe bottom, and mechanism constructed and arranged to maintain said roll initially in a rearward retracted and upraised position and for moving it forwardly and downwardly in automatic- 35
- ically determined relation to the movement of the shoe support to carry it into initial engagement with the bottom face of the toe end of the sole of the shoe. 40
17. In a leveling machine, a shoe support, a leveling roll, power-operated means for moving said shoe support in directions lengthwise of a shoe thereon to cause the roll to operate progressively along the shoe bottom, and automatic means for imparting to said roll positioning movement lengthwise of the shoe and also movement heightwise of the shoe toward the shoe bottom prior to the movement of the shoe support. 45
18. In a leveling machine, a shoe support, a leveling roll, power-operated means continuously under control of the operator for imparting to said shoe support movements in opposite directions at the will of the operator to cause the roll to operate progressively along the shoe bottom, and automatic means for moving said roll lengthwise of the shoe to a position over the toe end of the shoe bottom and for also moving it heightwise of the shoe into shoe-engaging position prior to the first movement of the shoe support. 50
19. In a leveling machine, a shoe support constructed to receive a shoe bottom upward with its toe end pointing rearwardly, a leveling roll, power-operated means continuously under control of the operator for imparting to said shoe support first a rearward movement and thereafter movements in opposite directions at the will of the operator to cause the roll to operate progressively along the shoe bottom, and means for moving the roll forwardly and downwardly in automatically determined relation to the first rearward movement of the shoe support to carry it into initial engagement with the bottom face of the toe end of the sole of the shoe. 55
20. In a leveling machine, a shoe support, a leveling roll, power-operated means for moving said shoe support in directions lengthwise of a shoe thereon to cause the roll to operate progressively along the shoe bottom, a roll carrier movable heightwise of the shoe, and automatic means for moving the roll lengthwise of the shoe relatively to said carrier and for also moving the carrier heightwise of the shoe to carry the roll into operating position substantially at the beginning of the operation of the machine. 60
21. In a leveling machine, a shoe support constructed to receive a shoe bottom upward with its toe end pointing rearwardly, a leveling roll, power-operated means for moving said shoe support in directions lengthwise of a shoe thereon to cause the roll to operate progressively along the shoe bottom, a roll carrier mounted for swinging movements heightwise of the shoe, spring means for moving said carrier downwardly to press the roll upon the shoe bottom, mechanism for imparting to the roll a forward positioning movement relatively to the carrier substantially at the beginning of the operation of the machine, a cam-operated lever for controlling said mechanism, and a device controlled by said lever for holding the carrier initially upraised and for releasing it to permit its downward movement as the roll is moved forwardly. 65
22. In a leveling machine, a shoe support, a leveling tool, power-operated means for moving said shoe support in directions lengthwise of a shoe thereon to cause the leveling tool to operate progressively along the shoe bottom, and automatic means for moving said leveling tool into initial engagement with the shoe on the 70

- bottom face of the toe end of the sole prior to the movement of the shoe support.
23. In a leveling machine, a shoe support, a leveling tool, power-operated means for moving said shoe support in directions lengthwise of a shoe thereon to cause the leveling tool to operate progressively along the shoe bottom, and automatic means for imparting to said leveling tool movement lengthwise and heightwise of the shoe to carry it into initial engagement with the shoe on the bottom face of the toe end of the sole prior to the movement of the shoe support.
24. In a leveling machine, a shoe support adjustable to position the ends of the toes of shoes of different sizes in substantially the same location, a leveling tool, power-operated means continuously under control of the operator for moving said shoe support in opposite directions at the will of the operator to cause the leveling tool to operate progressively along the shoe bottom, and mechanism movable in automatically determined relation to the movement of the shoe support to carry the tool into position to contact with each shoe initially in a location over the bottom face of the toe end of the sole.
25. In a leveling machine, a shoe support, a leveling tool, power-operated means for moving said shoe support in directions lengthwise of a shoe thereon to cause the leveling tool to operate progressively along the shoe bottom, and automatic means for imparting to said leveling tool a positioning movement lengthwise of the shoe in automatically determined relation to the movement of the shoe support prior to the operation of the tool upon the shoe and a reverse movement after the leveling operation.
26. In a leveling machine, a shoe support constructed to receive a shoe bottom upward with its toe end pointing rearwardly, a leveling roll, power-operated means for moving said shoe support in directions lengthwise of a shoe thereon to cause the roll to operate progressively along the shoe bottom, and power-operated means for imparting to said roll a forward positioning movement and for also moving it downwardly in automatically determined relation to the movement of the shoe support substantially at the beginning of the operation of the machine and for lifting it and moving it rearwardly after the leveling operation.
27. In a leveling machine, a shoe support constructed to receive a shoe bottom upward with its toe end pointing rearwardly, a leveling roll, power-operated means continuously under control of the operator for imparting to said shoe support first a rearward movement and thereafter movements in opposite directions at the will of the operator to cause the roll to operate progressively along the shoe bottom, and automatic means constructed and arranged to move the roll forwardly and downwardly prior to the first rearward movement of the shoe support and to lift it and move it rearwardly after the final forward movement of the shoe support.
28. In a leveling machine, a shoe support constructed to receive a shoe bottom upward with its toe end pointing rearwardly, a leveling roll, power-operated means continuously under control of the operator for imparting to said shoe support first a rearward movement and thereafter movements in opposite directions at the will of the operator to cause the roll to operate progressively along the shoe bottom, and automatic means for lifting the roll and moving it rearwardly when the shoe support in its forward movement arrives in a position in which the roll is in engagement with the toe end of the sole of the shoe.
29. In a leveling machine, a shoe support constructed to receive a shoe bottom upward with its toe end pointing rearwardly, a leveling roll, power-operated means continuously under control of the operator for imparting to said shoe support first a rearward movement and thereafter movements in opposite directions at the will of the operator to cause the roll to operate progressively along the shoe bottom, and mechanism comprising a cam-operated lever for lifting the roll and moving it rearwardly when the shoe support in its forward movement arrives in a position in which the roll is in engagement with the toe end of the sole of the shoe.
30. In a leveling machine, a shoe support, a leveling tool, power-operated means for moving said shoe support in directions lengthwise of a shoe thereon to cause the leveling tool to operate progressively along the shoe bottom, said means being so constructed as to terminate movement of the shoe support in one direction with the tool in engagement with the bottom face of the toe end of the shoe, and automatic means for thereafter withdrawing the tool from engagement with the shoe.
31. In a leveling machine, a shoe support constructed to receive a shoe with its toe end pointing rearwardly, a leveling roll, power-operated means continuously under control of the operator for moving said shoe support first rearwardly and thereafter forwardly and rearwardly at the will of the operator to cause the roll to operate progressively along the shoe bottom, said means being constructed to prevent forward movement of the shoe support beyond a position in which the roll is in engagement with the bottom face of the toe end of the shoe, and automatic means for lifting the roll from the shoe at the end of the final forward movement of the shoe support.
32. In a leveling machine, a shoe support constructed to receive a shoe with its toe end pointing rearwardly, a leveling roll, power-operated means continuously under control of the operator for moving said shoe support first rearwardly and thereafter forwardly and rearwardly at the will of the operator to cause the roll to operate progressively along the shoe bottom, said means being constructed to prevent forward movement of the shoe support beyond a position in which the roll is in engagement with the bottom face of the toe end of the sole, and means under control of the operator for tipping the roll about an axis extending lengthwise of the shoe while the roll is thus in contact with the toe end of the sole.
33. In a leveling machine, a shoe support, a leveling roll, power-operated means comprising a cam for moving said shoe support in opposite directions selectively at the will of the operator to cause the roll to operate progressively along the shoe bottom, mechanism for moving the roll into and out of contact with the shoe, and a cam controlling said mechanism and so formed and arranged in relation to said first-mentioned cam as to cause the roll to engage the shoe initially on the bottom face of the toe end of the sole prior to the movements of the shoe support and to withdraw from the same location on the shoe after the completion of the movements of the shoe support.
34. In a leveling machine, a shoe support adjustable to position the ends of the toes of shoes

- of different sizes in substantially the same location, a leveling roll, power-operated means continuously under control of the operator for moving said shoe support in opposite directions at 5 the will of the operator to cause the roll to operate progressively along the shoe bottom, and mechanism movable in automatically determined relation to the movements of the shoe support to carry the roll heightwise of the shoe into 10 position to contact with each shoe initially in a location over the bottom face of the toe end of the sole and to carry it reversely out of contact with the shoe when it is in the same relation to the sole. 15
35. In a leveling machine, a shoe support and a leveling tool relatively movable in directions lengthwise of a shoe on said support to cause the tool to operate progressively along the shoe bottom, a support for said tool movable heightwise 20 of the shoe to press the tool upon the shoe bottom, a member movable by the operator, and a device arranged to connect with said tool support in response to movement of said member and thereafter to withdraw the tool from the shoe in 25 response to further movement of the member. 30
36. In a leveling machine, a shoe support and a leveling tool relatively movable in directions lengthwise of a shoe on said support to cause the tool to operate progressively along the shoe bottom, a support for said tool movable heightwise 35 of the shoe, mechanism comprising a rod connected to said tool support for pressing the tool down on the shoe bottom, a treadle, and a device arranged to grip said rod in response to movement of the treadle and thereafter to act through the rod to lift the tool from the shoe in response to further movement of the treadle. 40
37. In a leveling machine, a shoe support, a leveling tool, power-operated means for moving said shoe support in directions lengthwise of a shoe thereon to cause the tool to operate progressively along the shoe bottom, an arm supporting said tool and mounted for swinging movements heightwise of the shoe, a member connected to 45 said arm, a treadle, and a device arranged to grip said member in response to movement of the treadle and thereafter to act through said member to withdraw the tool from the shoe in response to further movement of the treadle. 50
38. In a leveling machine, a shoe support, a leveling tool, power-operated means for moving said shoe support in directions lengthwise of a shoe thereon to cause the tool to operate progressively along the shoe bottom, an arm supporting 55 said tool and mounted for swinging movements heightwise of the shoe, power-operated means connected to said arm for pressing the tool upon the shoe bottom, and a device movable by the operator and arranged to act through said power-operated means to swing the arm in a direction 60 to withdraw the tool from the shoe. 65
39. In a leveling machine, a shoe support, a leveling tool, power-operated means for moving said shoe support in directions lengthwise of a shoe thereon to cause the tool to operate progressively along the shoe bottom, an arm supporting said tool and mounted for swinging movements heightwise of the shoe, power-operated means comprising a rod connected to said arm for pressing 70 the tool upon the shoe bottom, a treadle, and a device movable by the treadle for first effecting a connection with said rod and for thereafter moving the rod to lift the tool from the shoe. 75
40. In a leveling machine, a shoe support, a leveling roll, power-operated means continuously 80 under control of the operator for effecting relative movements of said shoe support and roll in opposite directions at the will of the operator to cause the roll to operate progressively along the shoe bottom, mechanism also continuously under control of the operator for tipping the roll laterally of the shoe, means for maintaining the roll in pressure-applying relation to the shoe without special attention on the part of the operator, and means to enable the operator at will 85 to withdraw the roll from contact with the shoe. 90
41. In a leveling machine, a shoe support, a leveling roll, power-operated means continuously under control of the operator for effecting relative movements of said support and roll in 95 opposite directions at the will of the operator to cause the roll to operate progressively along the shoe bottom, mechanism also continuously under control of the operator for tipping the roll laterally of the shoe, power-operated means including a spring for pressing the roll on the bottom of the shoe, and mechanism arranged to enable the operator at will to relax the pressure of the roll on the shoe. 100
42. In a leveling machine, a shoe support, a leveling roll, power-operated means continuously under control of the operator for effecting relative movements of said shoe support and roll in opposite directions at the will of the operator to cause the roll to operate progressively along 105 the shoe bottom, a hand-operated member for controlling said power means, mechanism comprising another hand-operated member for tipping the roll laterally of the shoe, means for maintaining the roll in pressure-applying relation to the shoe without special attention on the part of the operator, and treadle-operated mechanism arranged to enable the operator at will 110 to withdraw the roll from contact with the shoe. 115
43. In a leveling machine, a shoe support, a leveling roll, power-operated means continuously under control of the operator for effecting relative movements of said shoe support and roll in opposite directions at the will of the operator to cause the roll to operate progressively along 120 the shoe bottom, a hand-operated member for controlling said power means, mechanism comprising another hand-operated member for tipping the roll laterally of the shoe, mechanism including a spring for pressing the roll upon 125 the shoe bottom without special attention on the part of the operator, and treadle-operated means arranged to enable the operator at will to counteract the force of said spring. 130
44. In a leveling machine, a shoe support, a leveling roll, power-operated means continuously under control of the operator for effecting relative movements of said shoe support and roll in opposite directions at the will of the operator to cause the roll to operate progressively along 135 the shoe bottom, a hand-operated member for controlling said power means, mechanism comprising another hand-operated member for tipping the roll laterally of the shoe, an arm supporting the roll and movable heightwise of the 140 shoe, power-operated means including a rod connected to said arm for pressing the roll yielding upon the shoe bottom, and treadle-operated mechanism arranged to act on said rod at the will of the operator to relax the pressure of 145 the roll on the shoe. 145
45. In a leveling machine, a shoe support, a leveling roll, power-operated means continuously under control of the operator for imparting to said shoe support movements in opposite direc- 150

- 5 tions at the will of the operator to cause the roll to operate progressively along the shoe bottom, a hand-operated member for controlling said power means, mechanism comprising another hand-operated member for tipping the roll laterally of the shoe at the will of the operator, and automatic means for pressing the roll upon the shoe bottom without special attention on the part of the operator.
- 10 46. In a leveling machine, a shoe support, a leveling roll, power-operated means continuously under control of the operator for imparting to

80 said shoe support movements in opposite directions at the will of the operator to cause the roll to operate progressively along the shoe bottom, a hand-operated member for controlling said power means, mechanism comprising another hand-operated member for tipping the roll laterally of the shoe at the will of the operator, a roll support, and power-operated cam means arranged to act on said roll support to press the roll upon the shoe bottom.
